The ornamental design for a display screen with graphical user interface, as shown and described.

DESCRIPTION

FIG. 1 is a front view of a display screen with graphical user interface showing my new design;

FIG. 2 is a front view thereof in accordance to a second embodiment;

FIG. 3 is a front view thereof in accordance to a third embodiment;

FIG. 4 is a front view thereof in accordance to a fourth embodiment;

FIG. 5 is a front view thereof in accordance to a fifth embodiment; and,

FIG. 6 is a front view thereof in accordance to a sixth embodiment.

The outermost broken line perimeter showing the display screen and the broken lines showing elements of the graphical user interface are provided for the purpose of illustrating portions of the article and forms no part of the claimed design.
